WAX CHARGED APPLICATOR PAD

Russell B. Kingman, Orange, N. J.

Application October 2, 1937, Serial No. 167,045

4 Claims. (Cl. 91—54.7)

This invention relates to waxing pads which are charged with a content of expressible wax material which, in the use and manipulation of the pad, may be exuded from the operative face of said pad when the latter is rubbed upon and over a surface desired to be wax polished.

This invention has for an object to provide a novel form and construction of hand manipulatable pad or applicator comprising, a porous face member which may be made of textile material, felt, natural or artificial sponge material, or any other material through the interstices or pores of which the wax may be dispersed and exuded therefrom, said face member being provided with a backing member of wax impervious sheet material which is more or less flexible, and which is embossed to provide reserve wax storage elements opening toward the facing member; said storage elements being manipulatable by the fingers of the hand in which the pad is held and by which it is manipulated in operation, so that pressure may be exerted, at will, upon said elements, to force wax therefrom into the applicator facing member in renewal of the wax exuded from the latter during use of the pad.

Other objects of this invention, not at this time more particularly enumerated, will be understood from the following detailed description of the same.

Illustrative embodiments of this invention are shown in the accompanying drawing, in which:

Fig. 1 is a back face view of one form of wax charged applicator made according to this invention; and Fig. 2 is a transverse vertical section therethrough, taken on line 2—2 in said Fig. 1.

Fig. 3 is a back face view of another form of the wax charged applicator according to this invention; and Fig. 4 is a transverse vertical section through the same, taken on line 4—4 in Fig. 3.

Fig. 5 is a fragmentary back face view of still another form of the wax charged applicator made according to this invention.

Fig. 6 is a fragmentary sectional view of another modified form of the wax charged applicator pad.

Similar characters of reference are employed in the hereinabove described views, to indicate corresponding parts.

The novel wax charged applicator pad, in the form thereof shown in Figs. 1 and 2, comprises an applicator body or face member 10. This applicator body or face member may be made of any suitable soft porous material. For example, a fibrous or felt-like material is well adapted to

serve the purpose, since the pores or interstices thereof permits the same to be charged with a content of soft wax adapted to be exuded from the exposed or operative face thereof by pressure exerted thereupon when the pad is rubbed across a surface to which it is desired to apply the wax. Among other materials which may be used for said applicator body or face member 10 may be mentioned knitted or woven textile material, natural or artificial sponge, and, in fact, almost any kind of comparatively soft material through the body of which extend interconnected interstices into which the wax may be filled, and from which said wax may be exuded at the exposed or operative face thereof. The applicator body or face member 10 may be made of any desired peripheral shape and of suitable surface area.

Superposed upon the back face of said applicator body or face member 10 is a backing member 11, the same corresponding in peripheral shape and area to said applicator body or face member. Said backing member and applicator body or face member are secured together in assembled relation, preferably by stitching 12 sewn therethrough adjacently along the registered marginal portions thereof. Suitably secured to the pad body thus formed is a transverse hand attachment band or loop 13, arranged to extend across the pad back, and beneath which the hand of the user may be inserted so as to hold the pad thereto in use.

Said backing member is provided with a plurality of storage elements 14, the same being formed by outwardly pressed portions of the sheet of which the backing member is made, so as to provide reserve wax holding cavities 15 having their open sides or mouths disposed along the inner face of the backing member and contiguous to the opposed inner face of the applicator body or face member 10. Packed into the cavities 15 are masses of reserve wax 16.

In the arrangement of said storage elements 14, as shown in Figs. 1 and 2, the same are provided in the form of elongated longitudinally disposed hollow bosses which are spaced laterally apart to provide intervening finger receiving spaces 17. When using the pad thus formed, the operator initially disposes the fingers of the hand employed in manipulating the pad in the finger receiving spaces 17, and thereupon rubs the pad back and forth over the surface to which it is desired to apply the polishing wax. Under these conditions, the wax content dispersed through the interstices of the applicator body or face member 10 will first be exuded therefrom.

When the applicator body or face member, by such operation, tends to be exhausted by exudation of its wax content, the operator may shift the fingers of the pad manipulating hand so as to

- 5 engage therewith the storage elements 14, and, by exerting pressure thereon express from the cavities 15 thereof some of the reserve wax 16, which is thus forced into and through the pores or interstices of the applicator body or face member 10 in renewal of the wax previously discharged therefrom. It will be obvious, that by thus manipulating the flexible walled storage elements 14 from time to time renewed supplies of wax may be delivered into the applicator body, 10 or face member 10 at need, until finally the entire initial and reserve wax content of the pad is exhausted. It will be obvious that the dispositional arrangement, spacing, and conformation of the wax storage elements 14 is subject to 15 considerable variation.

In Figs. 3 and 4, there is shown a modified form and arrangement of wax storage elements, the same comprising a multiplicity of more or less closely spaced hollow embossments 18 open 20 toward the applicator body or face member 10, the cavities of which contain the reserve wax masses. In the use and manipulation of this type of pad, the operator initially presses the pad to the surface to be treated with but little 25 pressure, so that the initial wax content of the applicator body or face member is first expressed. As such initial wax content tends to become exhausted the operator will increase the pressure upon the pad back which will tend to collapse the 30 flexible wall embossments 18 so as to drive the reserve wax therefrom and into and through the applicator body or face member 10.

In Fig. 5 there is shown another arrangement of reserve wax storage elements which, in this 40 case, comprise rib-like embossments 19, which are subject to manipulation in substantially the same manner as last described.

In Fig. 6 there is shown another arrangement of reserve wax storage elements. In this arrangement a wax carrier member 20, having formed therein by collapsible embossments 21 of suitable shape, a plurality of reserve wax pockets or cavities 22, in which the reserve wax 45 masses 23 are stored. This carrier member 20 may be made of paper or like sheet material, and the same is disposed intermediate the previous applicator body or face member 24 and an impervious backing member 25. In the use and manipulation of this type of pad, the operator 50 also initially presses the pad to the surface to be treated with but little pressure, so that the initial wax content of the applicator body or face member is first expressed, whereafter by increasing the pressure the reserve wax 23 is forced from the pockets or cavities 22 into and through the applicator body or face member.

From the above description it will be apparent that a novel means for providing a waxing pad with a reserve wax supply is furnished, and it 55 will be understood that in specific form the embossed reserve wax containing cavities formed in the wax impervious backing member are subject to a great variation, and that in this and other respects many changes could be made in the 60 above described constructions, and many apparently widely different embodiments of this invention could be made without departing from the scope thereof as defined by the following claims. It is therefore intended that all matter contained

in the above description or shown in the accompanying drawing shall be interpreted as illustrative and not in a limiting sense.

I claim:

1. A wax charged applicator pad comprising, 5 an applicator body of porous character, a wax material dispersed through the interstices of said body for exudation from the outer face thereof, an external impervious backing member of sheet material secured to said body contiguous to the inner face thereof, said backing member having formed therein a plurality of hollow flexible walled storage elements providing cavities having open sides opposed and contiguous to the inner face of said body, and reserve wax masses 10 contained in the cavities of said storage elements, subject to expression therefrom into and through said applicator body by direct manipulation of the flexible walls of said storage elements. 15

2. A wax charged applicator pad comprising, 20 an applicator body of porous character, an external impervious backing member of flexible sheet material secured to said body contiguous to the upper face thereof and in covering relation thereto, said backing member having outwardly embossed hollow reserve wax storage elements 25 open along the under face of said backing member in opposition to the upper face of said applicator body, and said storage elements being 30 spaced apart to provide intervening finger receiving spaces adjacent thereto, whereby the flexible walls of said storage elements may be directly manipulated by the fingers to express 35 stored wax therefrom into and through said applicator body. 40

3. A wax charged applicator pad comprising, 45 an applicator body of porous character, a wax material dispersed through the interstices of said body for exudation from the exposed under face thereof, an external impervious backing member of flexible sheet material secured to said body contiguous to the upper face thereof and in covering relation thereto, said backing member having outwardly embossed hollow storage 50 elements open along the under face of said backing member in opposition to the upper face of said applicator body, and reserve wax masses contained in the cavities of said storage elements, subject to expression therefrom into and through said applicator body by direct manipulation of the flexible walls of said storage elements. 55

4. A wax charged applicator pad comprising, 60 an applicator body of porous character, a wax material dispersed through the interstices of said body for exudation from the outer face thereof, an external impervious backing member of flexible sheet material secured to said body contiguous to the upper face thereof and in covering relation thereto, said backing member having outwardly embossed hollow storage 65 elements open along the under face of said backing member in opposition to the upper face of said applicator body, reserve wax masses contained in the cavities of said storage elements, and said storage elements being spaced apart to provide intervening finger receiving spaces adjacent thereto, whereby the flexible walls of said storage elements may be directly manipulated by the fingers to express stored wax therefrom into 70 and through said applicator body. 75
